Application August 19, 1931, Serial No. 557,991
In the Netherlands January 16, 1931

3 Claims. (Cl. 250—27)

The invention relates to radio receiving circuit arrangements, and more particularly to the circuit arrangement of the detector.

In order to obtain a satisfactory selectivity it is desirable to utilize two tuned circuits of which one is included in the detector input circuit. Besides, the damping must be made as slight as possible, which is usually effected by providing retroaction whereby part of the output energy of a detector valve is fed back again to the input circuit. In order to obtain maximum selectivity the feed back is made so great that the tube is on the verge of oscillating. This circuit arrangement presents, however, the drawback that when the tuning is altered the damping is simultaneously modified. This drawback can be eliminated by altering the retroaction, due to which however the tuning is simultaneously modified again. Readjustment of the input circuit of the detector is consequently always needed so that it is practically impossible to mount the condensers required for the aerial and detector circuits on one shaft, and to adjust them simultaneously.

The present invention provides an installation with which the damping is independent of the tuning of the circuits. According to the invention a screen grid tube is used as the detector, the input circuit being connected between the control grid and the cathode, and the anode circuit including a circuit tuned to the frequency of the oscillations to be received, such positive potentials being applied to the anode and the screen grid that the tube is adjusted to the verge of self-oscillations. The potential of the screen grid is preferably chosen in this case so as to be high relatively to the anode voltage. It has been found that the amplitudes of the low frequency currents in the anode circuits are much smaller than those in the screen grid circuit. The output circuit is therefore preferably connected to the screen grid circuit.

The novel features which I believe to be characteristic of my invention are set forth in particularity in the appended claims, the invention itself, however, as to both its organization and method of operation will best be understood by reference to the following description taken in connection with the drawing in which I have indicated diagrammatically one circuit arrangement whereby my invention may be carried into effect.

The invention will be more clearly understood by referring to the accompanying drawing, in which

Fig. 1 represents a diagram of connections, and,

Fig. 2 a characteristic curve which represents the anode current as a function of the anode voltage at a determined screen grid voltage.

In Fig. 1, 1 is a screen grid tube comprising a cathode 2, a control grid 3, a screen grid 4, and an anode 5. A tuned input circuit 6, 7 is connected between the control grid and the cathode. The screen grid is connected through the primary winding of a transformer 8 to the positive terminal of a battery, the negative side of which is connected to the cathode, an intermediate point 10 of this battery being connected to the anode through a tuned circuit 11, 12. With the aid of the variable connection 10 the tube is adjusted on the verge of self-oscillation, i. e., on the point A, or B, of the characteristic curve shown in Fig. 2. The tube consequently acts as an anode detector.

The damping is exclusively regulated by displacing the point of connection 10. Variation of the anode voltage due to this displacement has no influence on the tuning of any of the circuits 6, 7 or 11, 12. For this reason it is possible to mount the condensers 6 and 11 utilized in these circuits on a single shaft, shown by dotted line 6'.

While I have indicated and described one arrangement for carrying my invention into effect, it will be apparent to one skilled in the art that my invention is by no means limited to the particular organization shown and described, but that many modifications may be made without departing from the scope of my invention as set forth in the appended claims.

What I claim is:

1. The combination in a receiving circuit of an electron discharge tube having a cathode, a control grid, an anode and a screen grid interposed between said control grid and anode, means for impressing suitable potentials on the screen grid and anode, the screen grid potential being of a higher value than that of the anode, an input circuit tunable to the signal frequency connected between the control grid and cathode, a second circuit tunable to the same frequency as the input circuit connected between the anode and cathode, and output coupling means connected to the screen grid.

2. The combination in a receiving circuit of an electron discharge tube having a cathode, a control grid, an anode and a screen grid interposed between said control grid and anode, means for impressing suitable potentials on

the screen grid and anode, the screen grid potential being of a higher value than that of the anode, an input circuit tunable to the signal frequency connected between the control grid and cathode, a second circuit tunable to the same frequency as the input circuit connected between the anode and cathode, means for simultaneously controlling both said tunable circuits, and output coupling means connected to the screen grid.

3. In a radio receiver, a detector stage employing anode circuit rectification comprising a tube including a cathode, control grid, an auxiliary grid and a plate anode positioned in the order named, a tuned circuit including a variable

condenser tuning element connected between the control grid and cathode, a tuned circuit including a similar variable tuning element connected between the anode and cathode, a source of positive potential for the anode and auxiliary electrode, and means for adjustably connecting the anode to a point of less positive potential on the source than the point to which the auxiliary electrode is connected, and means for simultaneously controlling the said tuning elements to tune the said circuits to a common desired signal frequency and means for coupling the auxiliary electrode circuit to a low frequency load circuit.

ROMYN VELDHUYZEN. 15
